UNITED STATES PATENT OFFICE.

HIDDEN EARL FREEMAN, OF CREWE, VIRGINIA.

DISPLAY CONTAINER.

Application filed November 7, 1923. Serial No. 673,314.

This invention relates to an improvement in boxes for containing and displaying confections or the like, and the object of the invention is to provide a box of this character which enables an attractive display of the confections and at the same time permits of and facilitates dispensing of the candy or confection contained in the box without the necessity of interfering with or disturbing the confection on display thereby preserving the attractive features of the display and facilitating the sale or dispensing of the confection.

Another object is to provide a box of this character and having these advantages and which is also of extremely simple construction and adapted to be cheaply and easily manufactured or produced.

Other objects and advantages of the invention reside in certain novel features of the construction, combination and arrangement of parts which will be hereinafter more fully described and particularly pointed out in the appended claim, reference being had to the accompanying drawings forming part of this specification, and in which:

Figure 1 is a view in side elevation, parts being broken away and shown in section and illustrating one embodiment of the invention;

Figure 2 is a perspective view of the candy box or container modified in accordance with the present invention;

Figure 3 is a perspective view of the wire frame shown in use in Figure 1; and

Figure 4 is a perspective view, illustrating a slightly modified means for supporting and maintaining the display tray in position.

Referring to the drawings, the numeral 10 designates a container or box adapted for the reception of candy or similar confection. As usual this box includes a bottom 11, side walls 12 and 13, a front end wall 14 and a rear end wall 15. The rear end wall 15 is cut away for a substantial portion of its extent, as clearly shown at 16, in Figure 2 and the large opening thus provided enables access to be had to the interior of the box through the rear end wall 15. At the same time enough of the end wall 15 is left to preserve the structural integrity and the strength of the box structure.

A display tray or holder, designated at 17, is provided and usually contains the top layer of confection which is utilized for

purposes of display. With the present invention it is proposed to leave this top layer intact and undisturbed while the contents of the box are being dispensed thereby preserving the attractive features of the display. In carrying out this purpose means is provided for supporting the display tray at an angle above the box with its rear end vertically spaced above the rear end of the candy box. This arrangement places the tray in the most attractive position for display and at the same time facilitates access to the interior of the box and to the contents thereof through the rear end. In the form of the invention shown in Figures 1 to 3 this means includes a wire frame, designated generally at 18, and comprises two pieces of wire, designated at 19 and 20, the pieces of wire being intertwined, as at 21, intermediate their ends. The front ends of the wire are designated at 21 and 22 respectively, the rear ends at 23 and 24 respectively, and as clearly shown in Figure 3, the front ends as well as the rear ends extend away from each other in diverging relation. The front ends 21 and 22 are formed with upwardly and vertically extending portions designated at 25 and 26, which constitute legs and which terminate in hooks 27 and 28. Similarly the rear ends 23 and 24 are formed with downwardly or depending vertically disposed portions 29 and 30 which also constitute legs and which terminate in hooks 31 and 32. As shown in Figure 1 the frame 18 is supported on the box 10 with the hooks 27 and 28 engaging over the upper edge of the front wall 14 and with the hooks 31 and 32 engaging over the upper edges of the side walls 12 and 13 adjacent the rear end of the box. In view of the fact that the legs 25 and 26 extend upwardly whereas the legs 29 and 30 extend downwardly the body of the frame (made up of the arms proper and the intertwined portions of the wires) is disposed at an angle with the rear end of the frame well above the rear end of the box and the front end of the frame slightly below the top of the front end of the box. The display tray 17 rests on the frame and its front end engages the legs 25 and 26 to hold the tray against forward and downwardly sliding movement. The rear end of the tray is supported well above the rear end of the box, and this together with the arrangement whereby the tray is supported on the side walls of the box greatly

facilitates access to the interior of the box through the rear end. It is to be understood that the wire of which the frame 18 is made is sufficiently resilient or bendable as to be susceptible of being bent and twisted or otherwise formed as above described, and as shown in the drawings while at the same time it is of such character as to preserve its completed form in use.

10 In the arrangement shown in Figure 4 a slightly modified form is disclosed for supporting the tray 17. With this arrangement the wire frame 18 is dispensed with and in lieu thereof strips of pasteboard or other suitable material designated at 36 and 36 are pasted or otherwise suitably secured to the end of the tray structure. The strip 35 carries legs 37 and 38 and the strip 36 carries legs 39 and 40. These legs are connected to their strips so as to be adapted to be folded into parallelism of the strips or to be extended at right angles thereto. When extended at right-angles to the strips they are adapted to support the box and when folded up against the strips the tray is adapted to be inserted in the candy box as the top layer. Obviously the legs 39 and 40 must be provided somewhat longer than the legs 37 and 38 in order to give the tray the requisite inclination and to space the rear end thereof well above the rear end of the candy box. Any suitable means may be provided for connecting the legs 38, 39 and 40 to their strips so that they can be folded or extended as above described. If the material of which the strips and legs are constructed permits, the same may be simply creased or provided with lines of fold at the point where the legs proper connect with the strips and if

not short strips of canvas or other suitable fabric may be pasted on the strips and the legs to provide a hinge between the legs and the strips. In the latter instance the legs of course are separate from the strips.

Irrespective of the character of the specific means employed for supporting the tray on the box it is so arranged in use as to most attractively display the upper or top layer of the confection and yet admit of access to the interior or contents of the box through the rear end thereof and thus facilitate the dispensing of the confection while leaving the top layer intact and undisturbed for purpose of display.

I claim:

A box for containing confection or the like having its rear end cut away to enable access to be had to the interior of the box through the rear end, in combination with a display tray, and means for supporting the tray at an angle on the said box with its front end at the level of the front of the box and its rear end vertically spaced above the rear end of the box, said means including a wire frame constructed of two pieces of wire intertwined intermediate their ends and having their front ends extending from each other in diverging relation and their rear ends extending from each other in diverging relation, the extremities of the front ends being formed with upwardly offset hooks engageable over the front wall of the box, the rear ends having portions disposed to constitute vertical legs and terminating in hooks engageable over the side walls of the box adjacent its rear end.

HIDDEN EARL FREEMAN.
